UNITED STATES PATENT OFFICE.

ELEUTHERE PAUL DU PONT, OF MONTCHANIN, DELAWARE.

LUBRICATING SYSTEM FOR INTERNAL-COMBUSTION ENGINES.

1,391,722.

Specification of Letters Patent. Patented Sept. 27, 1921.

Original application filed February 25, 1919, Serial No. 279,083. Divided and this application filed September 11, 1919. Serial No. 323,181.

To all whom it may concern:

Be it known that I, ELEUTHERE PAUL DU PONT, a citizen of the United States, residing at Montchanin, county of New Castle, 5 and State of Delaware, have invented a new and useful Improvement in Lubricating Systems for Internal-Combustion Engines; of which the following is a full, clear, and exact description, reference being had to the 10 accompanying drawings, which form a part of this specification.

This application is a division of an application for patent for improvement in internal combustion engine, filed February 25, 15 1919, Serial No. 279,083.

The object of my invention is to provide improved means for lubricating the moving parts of an internal combustion engine, which will be both simple in construction 20 and efficient in operation.

My invention comprises a well formed in the crank case for the accumulation of oil and a pump, in the case, driven from the engine crank shaft, whereby the oil is delivered through a sight feed to the desired parts. At the same time the usual oil level is carried in the crank case and the oil churned into mist by the cranks. An air current is provided whereby the oil mist 25 is carried to and deposited on the valve operating mechanism and all other parts in its path. My invention also comprises other structural features which are hereinafter fully described.

In order that my invention may be fully understood, it is deemed advisable to describe fully the casing or housing for the engine, which is the subject-matter of the 30 claims of the aforementioned application of which this is a division.

Figure 1 is a general view of the main castings, shown in perspective and separated from each other.

Fig. 2 is a vertical cross-section taken 45 through one of the cylinders showing in general the main parts only.

Fig. 3 is a similar cross-section taken through the hood containing the pump drives, etc.

The main casting *a*, forming the crank 50 and gear casing, is of generally cylindrical form with the front sliced away longitudinally as shown in Fig. 1. The top of this casing is flattened as at *b*, to which the cyl-

inder castings *c*, *c*, and the hood *d* are 55 bolted.

Transverse webs in casing *a* carry bearings *e* for the crank shaft 20 between and on either side of the cylinders. These bearings are arranged at an angle as stated and 60 provided with removable caps for conveniently inserting and extracting the crank shaft.

The crank shaft is formed between bearings *e* with the usual integral cranks for 65 actuation from the cylinders and extends only a short distance at both ends beyond the end bearings. At its forward end the shaft carries a fly wheel, not shown, located in the circular open end of the main casing 70 and arranged to be entirely inclosed by the circular end cover *f*.

At the opposite end the casing forms a compartment *g* between its end wall and the after bearing *e* in which is located the 75 reverse gearing, etc. At this end the crank shaft is provided with a flanged coupling (not shown) right next to the bearing, and by this coupling connects with an extension which operates the reverse gears and passes 80 on out the rear of the compartment where it is supported in bearings in a bonnet *h* arranged to be bolted to the end of casing *a*.

The entire open front of the casing is flanged and arranged to be closed by a 85 single front plate *i*. The cylinder castings *c*, *c* have open front compartments for containing the valve operative cams *j*, and also carry the bearings *k* for the cam shaft. These compartments are flanged in alignment with the flange on the front of casing 90 *a* so that they are also closed by front plate *i* which is provided with projections *l* for covering these compartments.

The crank compartments in casing *a* between bearings *e* are each provided at the back with an air inlet *m* as shown in Fig. 2. As shown in this figure, the valve operating mechanism is indicated at *n*, and it is completely inclosed at the top by light casing *o*. 100 From this casing a pipe *p* leads to the suction of the vaporizer *q* and thence to the inlet passage *r* in the cylinder head.

The operation is as follows: The cranks *s* dip into a bath of oil in the bottom of the casing, and in their rapid rotation churn the oil into a mist or spray which permeates the whole interior of the casing and cylin-

ders. Air enters the inlets *m* and passing through the casing becomes laden with particles of oil due to the splash action of the cranks, and carries them up about the valve 5 operating mechanism, as indicated by the arrows in Fig. 2, and thence passes through pipe *p* to the carburetor. By this time it has lost practically all of its oil particles, which have been deposited on the moving 10 parts in its path, thereby insuring their thorough lubrication.

Thus a continuous, yet rather slow, circulation of air is provided from the inlets, through the crank compartments, where it 15 gets heated, to the mixing chamber of the carburetor, on its way lubricating the cams and valve mechanism.

The end compartment *g* carries gearing *t* for operating the cam shaft *u*,—see Fig. 3. 20 On the shaft of one of these gears is conveniently mounted an eccentric *v* for actuating the rocker *w* for operating the pumps *x*, *y* and *z*; *x* representing the air pump, *y* the pump for supplying water to the cooling 25 jackets, and *z* a pump for removing the bilge water.

As will be seen in the drawing, the front plate *i*, where it covers this portion of the casing, is dished out and carries pumps *y* 30 and *z* on its face, operable by a single plunger 5 which is actuated by the slotted end of arm 6 of rocker *w*. The air pump *x* is operated by a link 7 connected with another arm of rocker *w*.

35 Rocker *w* also operates the oil pump 8 in the following manner: At this point the casing is cut out at the bottom, as shown at 9, and the dished portion of the front plate *i* is extended down to meet it and form therein an 40 oil pocket or well 10. Into this pocket extends oil pump 8 which is mounted to slide on a fixed plunger 11 comprising a pipe carrying at its lower end inlet valve 12 and at its upper end connecting with the sight 45 feed arrangement 13, from which a tube 14 provides lubrication for the gearing *t* and other mechanism in hood *d* and another tube 15 leads to the forward end of the engine, where oil overflows various divisions 50 in the crank case, finally returning to the bath in the bottom of the casing.

Pump 8 carries an inlet valve 16 at its lower end and is operated to raise and lower upon pipe 11 by means of a pin 17 on rocker 55 *w*, being held thereon by a spring 18 abutting against a collar on the pipe. The action of the pump is as follows: As the rocker is turned to lower pin 17, spring 18 forces pump 8 down into the oil in well 10, 60 and oil enters inlet valve 16. Upon the upstroke of the rocker, pin 17 raises the pump and the oil contained in its lower end is forced through valve 12 into pipe 11. As this is a continuous process, a certain quantity 65 of oil is kept circulating through pipes

14, 15, as can be ascertained by the sight feed 13.

The sight feed 13 may be replaced by a pressure gage and the oil sent, under pressure, from the pump to the crank shaft 70 bearings, thence through a hollow crank shaft to the crank pin bearings. Excess oil will be thrown out of these bearings and form a mist of oil in the case, which will be picked up and distributed by the air current as above described.

The advantages of this arrangement are that a great deal is accomplished by a very few parts. A single eccentric operates the four pumps, the lubrication of every moving part is provided from a single oil delivery pipe, and complete accessibility is afforded to each pump without disturbing any other working part.

Having now fully described my invention, 85 what I claim and desire to protect by Letters Patent is:

1. In an internal combustion engine, the combination with the cylinders and moving parts including the crank shaft, of mechanism driven from the crank shaft, an oil pump, driven from said mechanism, said pump including a fixed hollow piston up through which the oil is forced and a movable cylinder, and means to distribute the oil 95 forced from the upper part of the piston to working parts of the engine.

2. In an internal combustion engine, the combination with the cylinders and moving parts including the crank shaft, of mechanism driven from the crank shaft, an oil pump, driven from said mechanism, said pump including a fixed vertical pipe up through which the oil is forced, means to inclose said driving mechanism and oil 105 pump, a removable sight feed at the top of the oil pump and supporting the same whereby by lifting the sight feed the oil pump may be withdrawn, and oil distributing means connected with the sight feed.

3. In an internal combustion engine, the combination with the cylinders and moving parts including the crank shaft, of mechanism driven from the crank shaft, a vertically extending oil pump operable from said driven mechanism, a casing inclosing said driven mechanism, and a front plate closing the casing and inclosing the pump on three sides.

4. In an internal combustion engine, the combination with the cylinders and moving parts including the crank shaft, of mechanism driven from the crank shaft, an oil pump driven by said mechanism, and a fixed vertical delivery pipe extending interiorly of and forming an element of said oil pump and delivering oil therefrom.

5. In an internal combustion engine, the combination with the cylinders and moving parts including the crank shaft, of mecha-

nism driven from the crank shaft, an oil pump in driven relation with said mechanism, said pump including a vertical pipe up through which the oil is forced, a removable sight feed at the top of said oil pump and supporting the same, whereby by lifting the sight feed the oil pump may be withdrawn without disturbing the driving mechanism.

- 5 10 6. In an internal combustion engine, the combination with the cylinders and moving parts including the crank shaft, of mechanism driven from the crank shaft, an oil pump operable from said driven mechanism, said pump comprising telescoping tubes, valves at the lower ends of the tubes, means to actuate one of said tubes in one direction from the driven mechanism, and means independent of the driven mechanism to actuate said tube in the opposite direction.
- 15 20 7. In an internal combustion engine, the combination with the cylinders and moving parts including the crank shaft, of mechanism driven from the crank shaft, a vertically extending oil pump operable from said driven mechanism, said pump comprising telescoping tubes, valves on the lower ends of the tubes, collars on the tubes, a spring between the collars, means to positively actuate one of said tubes in one direc-

tion from the driven mechanism, the spring operating such tube in the opposite direction.

8. In an internal combustion engine, the combination with the cylinders and moving parts thereof including the crank shaft, of an open faced housing for inclosing the moving parts, a cover for the opening in said housing, a pocket in said cover forming an oil well, a pump extending into said oil well, an eccentric on the shaft, an arm adapted to be rocked by said eccentric, means for operating the pump from the arm, and means to lead the pumped oil to the moving parts of the engine.

45 9. In a lubricating system for an internal combustion engine having a crank case, there being an oil well in the crank case, a pump having a fixed hollow plunger and a movable cylinder, valves in the plunger and the cylinder, actuating connections between the pump cylinder and the engine, an oil reservoir in communication with the upper end of the hollow plunger, and oil feed pipes leading from said reservoir to the engine 50 parts for conveying oil thereto.

In testimony of which invention, I have hereunto set my hand, at Wilmington, Del., on this 28th day of August, 1919.

ELEUTHERE PAUL DU PONT.
